United States Patent Office

Des. 185,353
Patented June 2, 1959

185,353

FAUCET UNIT OR SIMILAR ARTICLE

Henry Dreyfuss, South Pasadena, Calif., assignor to Crane Co., Chicago, Ill., a corporation of Illinois

Application August 7, 1958, Serial No. 52,099

Term of patent 14 years

(Cl. D91—3)

Fig. 1 is a perspective view of a faucet unit embodying my new design;

Fig. 2 is a side elevational view thereof; and

Fig. 3 is a top plan view thereof.

I claim:

The ornamental design for a faucet unit or similar article, substantially as shown.
